UNITED STATES PATENT OFFICE.

BENJAMIN SKIDMORE, JR., OF CHICAGO, ILLINOIS.

HYDRAULIC AIR-COMPRESSOR AND VACUUM-PRODUCER.

1,392,856.

Specification of Letters Patent.

Patented Oct. 4, 1921.

Application filed August 12, 1918. Serial No. 249,500.

To all whom it may concern:

Be it known that I, BENJAMIN SKIDMORE, Jr., a citizen of the United States, residing at Chicago, in the county of Cook and State 5 of Illinois, have invented certain new and useful Improvements in Hydraulic Air-Compressors and Vacuum-Producers, of which the following is a specification.

This invention relates to improvements in 10 hydraulic air compressors and vacuum producers, and has for one of its objects to provide improved means embodying a rotatable element for removing a portion of liquid from a body or supply of liquid and which 15 element also operates to deliver air or gaseous fluid into the said body or supply to replace the liquid removed therefrom.

In my application Serial No. 216618, I 20 have described an improved apparatus of this character in which the rotatable element is given its motion and its operation by a column of liquid operating thereon, but it is one of the objects of the present invention to provide improved means whereby the circulation of a supply or body of liquid will 25 operate directly upon the said element at a tangent thereto to assist in rotating or actuating the element. In my application, Serial No. 249755, I employ a rotatable element 30 for transferring fluid and liquid from one container to another, but in said application the element is rotated by external mechanical means.

A further object is to provide an improved apparatus of this character for producing either a vacuum or a compression.

To the attainment of these ends and the accomplishment of other new and useful objects as will appear, the invention consists 40 in the features of novelty in substantially the construction, combination and arrangement of the several parts, hereinafter more fully described and claimed and shown in the accompanying drawings illustrating this 45 invention and in which:

Figure 1 is a vertical sectional view of an improved apparatus of this character constructed in accordance with the principles of this invention.

50 Fig. 2 is a vertical sectional view taken on line 2-2, Fig. 1.

Fig. 3 is a vertical sectional view of another form of the invention.

55 Fig. 4 is a detail sectional view of another form of the invention.

Referring more particularly to the draw-

ing, in Fig. 1 there is shown an adaptation of the invention in connection with a waterfall or elevated body of water 10, coöperating with which is a rotatable element 11 located 60 at any desired or suitable distance below the body of water and disposed within a chamber 12, the latter being preferably open at its bottom as at 13, so that liquid in the chamber 12 will be discharged by the element 11, when the latter is rotated, through the opening 13.

The element 11 is mounted to rotate upon a shaft 14 journaled in suitable bearings 15, and the element is disposed within a casing 70 or housing 16, the latter being arranged within and spaced from the walls of the chamber 12. The walls of the housing stand in close proximity to the periphery of the element 11, which latter is provided with a 75 series of radially projecting faces 17 spaced from each other, and having inclined portions 18 disposed intermediate the faces 17, so as not to interfere with the rotation of the element 11. The housing 16 is provided 80 with an opening 19 which communicates with the chamber 12 and an opening 20 which communicates with the open bottom 13 of the housing, so that when the element 11 is rotated, predetermined quantities of 85 liquid in the chamber 12 will be trapped in the pockets formed between the faces 17 and the walls of the housing 16 to be delivered through the opening 13, and predetermined quantities of air or gaseous fluid 90 will also be trapped between the pockets of the element 11 and the wall of the housing 16 to be delivered into the chamber 12.

The liquid 10 is conveyed to the element 11 and into the chamber 12 preferably by 95 means of a delivery pipe 21. The discharge outlet 22 which communicates with the chamber 12 adjacent the element 11, is disposed at a tangent to the element 11, so that the inflow of the liquid through the passage 100 21 and out of the discharge outlet 22 will impinge the faces 17 of the element 11 and thereby rotate the same. The air or gaseous fluid which is conveyed by the element 11 into the chamber 12 will pass in the form 105 of bubbles into the chamber 12, and into a suitable reservoir 23, arranged at a suitable elevation, and which reservoir 23 has communication by means of an extension 24 with the chamber 12. The reservoir 23 is 110 provided with a discharge outlet pipe 25 having a controlling valve 26 therein, so

that a compression may be obtained in the reservoir 23.

The liquid will flow through the inlet 21 and into the chamber 12 as long as the pressure on the inflowing liquid is greater than the pressure upon the liquid in the chamber 12 and during the rotation of the element 11, predetermined quantities of the liquid in the chamber 12 will be delivered by the element 11 out of the opening 13, but when the pressure in the reservoir 23 counterbalances the pressure in the inlet 21, the element 11 will cease to rotate.

The air or gaseous fluid which remains in close proximity to the element, as it is discharged into the chamber 12, may be removed from the element and directed into the chamber in any suitable manner such as by means of a stripper plate 27.

20 In the form of the invention shown in Fig. 3, the element 11 is arranged between superposed reservoirs 28—29, and the liquid from the reservoir 28 will be delivered into the reservoir 29 as the element 11 rotates, 25 and which rotation is produced by means of a centrifugal pump 30 which receives its supply through an inlet 31 having communication with the reservoir 29. The liquid is delivered from the pump 30 through the discharge pipe 32 having an outlet 33 delivering into the reservoir 28 adjacent the periphery of the element 11, and at a tangent thereto, so that the liquid which is being transferred from the reservoir 29 into the reservoir 28 35 operates upon the element 11 to rotate it, and thereby intermittently delivers predetermined quantities of the liquid into the reservoir 28 from the reservoir 29. At the same time, air or gaseous fluid will be withdrawn 40 from the reservoir 29 by the element 11 and discharged into the reservoir 28 through the liquid therein in the form of bubbles, and the air or gaseous fluid may be directed away from the periphery of the element 11 45 by means of the stripper plate or element 27. The suction or partial vacuum created in the reservoir 29 will be manifested in a pipe or passage 34, and the reservoir 28 is provided with a discharge outlet 35 having 50 a valve 36 therein and which valve may be closed, so that a compression may be obtained in the reservoir 28. The production of the compression is obtained by maintaining the liquid in the reservoir 28 at a 55 substantially constant level.

In Fig. 4 the rotary element 37 is provided with a plurality of laterally projecting wings 38, producing spaces 39 therebetween to form buckets or pockets for receiving the liquid.

What is claimed as new is:—

1. In combination, means embodying a rotatable element for removing a portion of liquid from a supply of liquid, the said 65 element also operating to deliver air or a

gaseous fluid into the said supply of liquid to replace the liquid removed therefrom by the said element, and provisions for inducing circulation of a portion of the said supply or body of liquid against one portion of the said element and at a tangent thereto, to rotate the element and cause another portion of the element to operate to remove a portion of the liquid. 70

2. In combination, means embodying a rotatable element for removing a portion of liquid from a supply of liquid, the said element also operating to deliver air or a gaseous fluid into the said supply of liquid to replace the liquid removed therefrom by the said element, and provisions for inducing circulation of a portion of the said supply or body of liquid against one portion of the said element to rotate the element and cause another portion of the element to operate to remove a portion of the liquid, the said provisions embodying a supply 80 passage having an outlet communicating with the said body or supply of liquid, the said outlet being disposed at a tangent to 85 the said element.

3. In combination, means embodying a rotatable element for removing a portion of liquid from a supply of liquid, the said element also operating to deliver air or a gaseous fluid into the said supply of liquid to replace the liquid removed therefrom by the said element, provisions for inducing circulation of a portion of the said supply or body of liquid against one portion of the 95 said element to rotate the element and cause another portion of the element to operate to remove a portion of the liquid, and means disposed adjacent the periphery of the said element for removing the air or gaseous 100 fluid from the periphery of the said element and directing the same into the said body or supply of liquid. 105

4. An apparatus of the character described embodying a rotatable element, a reservoir for impounding a desired quantity of liquid at a desired elevation above said element whereby the element when rotated will intermittently deliver predetermined quantities of the liquid from the reservoir, 110 and means for delivering the liquid to the reservoir, the said means embodying a liquid passage having an outlet discharging into the reservoir against the said element and at a tangent thereto to rotate the element, 115 said element also operating to intermittently deliver predetermined quantities of a gaseous fluid or vapor into the reservoir to replace the liquid removed therefrom by the said element. 120

5. An apparatus of the character described embodying a rotary element, a reservoir for impounding a desired quantity of liquid at a desired elevation above said element whereby the said element when rotated will 125 130

- deliver the liquid from the reservoir intermittently and in predetermined quantities, a reservoir for receiving the liquid discharged by the element, and means for transferring the liquid from the second recited reservoir back into the first recited reservoir, against the said element at a tangent thereto to rotate the element, the said element also operating to withdraw predetermined quantities of a gaseous fluid or vapor from the second recited reservoir to create a suction therein and deliver the said fluid or vapor into the first recited reservoir to replace the liquid withdrawn therefrom.
6. An apparatus of the character described embodying a rotary element, a reservoir for impounding a desired quantity of liquid at a desired elevation above said element whereby the said element when rotated will deliver the liquid from the reservoir intermittently and in predetermined quantities, a reservoir for receiving the liquid discharged by the element, and means for transferring the liquid from the second recited reservoir back into the first recited reservoir, against the said element at a tangent thereto to rotate the element, the said element also operating to withdraw predetermined quantities of a gaseous fluid or vapor from the second recited reservoir to create a suction therein and deliver the same into the first said reservoir through the liquid therein to be compressed in the first said reservoir.
7. An apparatus of the character described embodying a rotary element, a reservoir for impounding a desired quantity of water at a desired elevation above said element to be delivered to the element, a reservoir for receiving water discharged by said element, means for rotating the element, means whereby the rotation of the element will withdraw fluid or vapor from the second recited reservoir and deliver the same into the first recited reservoir, and means for transferring the liquid from the second recited reservoir to the first recited reservoir and delivering the liquid into the first recited reservoir adjacent and at a tangent to the periphery of the said element.
8. An apparatus of the character described embodying a rotary element, a reservoir for impounding a desired quantity of water at a desired elevation above said element to be delivered to the element, means for rotating the element whereby the element will deliver the water from the reservoir, said element also operating to deliver fluid or vapor into the reservoir and through the liquid therein, and means for delivering a supply of water into the reservoir against the periphery of the said element and at a tangent thereto.

In testimony whereof I have signed my name to this specification, on this 8th day of August, A. D. 1918.

BENJAMIN SKIDMORE, JR.
